[57] CLAIM

The ornamental design for a combined closure member and diaphragm, as shown and described.

DESCRIPTION

FIG. 1 is a top perspective view of a combined closure member and diaphragm showing our new design; FIG. 2 is a side elevational view with the lugs up and the diaphragm omitted;

FIG. 3 is a top plan view thereof;

FIG. 4 is a top elevational view thereof;

FIG. 5 is a bottom plan view thereof;

FIG. 6 is a front elevational view with the lugs down and the diaphragm omitted;

FIG. 7 is a bottom plan view thereof;

FIG. 8 is a side elevational view thereof;

FIG. 9 is a top plan view thereof;

FIG. 10 is a front elevational view with the diaphragm in place;

FIG. 11 is a bottom plan view thereof; and

FIG. 12 is a bottom perspective view with the diaphragm omitted.

The views of the opposite side to that shown in FIGS. 2, 4, 6, 8 and 10 are not shown as they are mirror images.

FIG. 1.

FIG. 2.
